CLAIM

I claim the ornamental design for a recess ceiling fan bezel, as shown and described.

DESCRIPTION

FIG. 1 is a bottom perspective view of a recess ceiling fan bezel, showing my new design;

FIG. 2 is a bottom plan view thereof;

FIG. 3 is a top plan view thereof;

FIG. 4 is a right-side elevational view thereof;

FIG. 5 is a left-side elevational view thereof;

FIG. 6 is a front elevational view thereof;

FIG. 7 is a rear elevational view thereof; and,

FIG. 8 is a cross-sectional view thereof, taken along line 8-8 of FIG. 2.

The broken lines showing fan blades in FIG. 1 depict environmental matter and form no part of the claimed design.
